SWAB ASSEMBLY

Jack C. Webber, Corpus Christi, Tex., assignor to Mission Manufacturing Company, Houston, Tex., a corporation of Delaware

Filed Apr. 25, 1966, Ser. No. 544,902

8 Claims. (Cl. 92—180)

ABSTRACT OF THE DISCLOSURE

This patent shows a mandrel and swabs for swabbing a well in which alternate lands and grooves are provided on a fluted mandrel. The alternate lands and grooves permit the swab rubbers to misalign as the swab is run into the well and align the swabs as it is removed from the well.

This invention relates to swab assemblies for swabbing wells.

It is frequently necessary to remove liquid standing in a petroleum well to start the well flowing. This is conventionally done by a swab which is lowered into the well to a point under a desired amount of liquid. The swab is then raised to remove liquid from the well. In this manner the liquid is removed from the well until it begins to flow.

Well tubing is seldom straight and true. Frequent tight spots and eccentric points are encountered. Where a plurality of swab rubbers are employed on a single mandrel, they sometimes bridge across eccentric areas or tight spots. When this occurs, difficulty is experienced in getting the swab to fall down the tubing.

Swabs of the type which employ a movable swab rubber on a mandrel which functions as a check valve sometimes become sanded up and resist movement on the mandrel due to the relatively close tolerance between the mandrel and the bore through the swab.

It is an object of this invention to provide a swab assembly which will readily fall through crooked or misaligned sections of tubing without impairing the efficiency of the swab assembly.

Another object is to provide a mandrel and swab assembly in which swab rubbers may be misaligned individually with the mandrel while being run into the well, and which are returned to aligned condition during swabbing.

Another object is to provide a swab assembly which is less likely to sand up due to large clearances between the mandrel and most of the area of the swab rubber.

Other objects, features and advantages of the invention will be apparent from the drawings, the specification and the claims.

In the drawings, wherein an illustrative embodiment of this invention is shown, and wherein like numerals indicate like parts;

FIGURE 1 is a view partly in elevation and partly in section through a swab assembly constructed in accordance with this invention with the swab assembly shown moving downwardly through a well tubing;

FIGURE 2 is a fragmentary view similar to FIGURE 1 showing the swab assembly moving upwardly in the well and lifting a load of liquid; and

FIGURE 3 is a sectional view along the line 3—3 of FIGURE 1.

In accordance with this invention, the mandrel and swab rubbers are arranged in such manner that with the swab rubbers in their upper position they may tilt about the mandrel to a nonaligned position. This is accomplished by providing clearance between the extremities of the swab rubber and the mandrel which will permit relative misalignment. This concept is carried out with

2

each swab on the mandrel and when the swab rubbers are in their upper position during falling of the swab assembly, each swab rubber may individually misalign with the other swab rubbers and the mandrel.

At the beginning of the swabbing operation when the mandrel is pulled upward, the swab rubbers move to their down position where they are held in aligned position with each other and with the mandrel by a pair of spaced lands on the mandrel. It might be noted that these lands occupy an intermediate position of each swab rubber during running so that the swab rubbers may misalign, as discussed above.

Referring now to the drawings, a well tubing comprising tubing sections 10 and 11 are shown to be eccentrically connected. The amount of eccentricity is exaggerated but illustrates the manner in which an eccentricity can occur. Many other tubing conditions also occur which make it difficult to pass two or more swab rubbers which are held in aligned position.

Within the tubing there is shown a mandrel indicated generally at 12 which is suspended from a wireline 13. The mandrel 12 is shown to be misaligned relative to the tubing. Again, the degree of misalignment is exaggerated for purposes of illustration.

A plurality of swab rubbers indicated generally at 14 are carried on the mandrel. Two swab rubbers are shown in full line and a third swab rubber is shown in dotted line to illustrate that one or more swab rubbers may be carried on the mandrel, depending upon the amount of fluid to be lifted. While this invention has its greatest usefulness where two or more swab rubbers are present, it will be appreciated that the invention is also useful where only a single swab rubber is used, as the ability of even a single swab rubber to misalign relative to the mandrel permits greater freedom in running the swab assembly downwardly in the tubing. A full description of the type of swab rubber illustrated is found in Webber Patent No. 2,633,808.

Referring to the mandrel in detail, it is seen to comprise an upper section indicated generally at 15, an intermediate section indicated generally at 16, and a lower section indicated generally at 17. The several swab rubbers 14 are mounted on the intermediate section for loose engagement therewith and for movement axially of the mandrel.

The intermediate section of the mandrel 16 is provided with a plurality of lands 18, 19, 20 and 21. These lands alternate with grooves 22, 23, 24 and 25. The lands and grooves extend circumferentially about the intermediate section of the mandrel.

Provision is made for flow of fluid through the swab assembly. This may be carried out in any desired manner. In the illustrated embodiment of the invention a plurality of flutes 26 are provided. These flutes extend through the intermediate section of the mandrel and a portion of the top section of the mandrel 15.

The top section of the mandrel 15 is enlarged relative to the lands and provides a shoulder 27 which serves as a stop to limit relative movement of the swabs.

The lower section of the mandrel 17 is also enlarged relative to the lands and grooves and provides a stop 28 for limiting downward movement of the swab rubbers relative to the mandrel.

The several lands and grooves are arranged so that they permit the several swab rubbers to misalign relative to the mandrel when in their upper position, and hold the swab rubbers in alignment when in their lower position. The distance from shoulder 27 to the center of land 18 is approximately half the distance from center to center of lands 18 and 19. The distance from center to center of lands 18 and 19 is the same as the distance from center

to center of lands **19** and **20**. The distance from center of land **20** to shoulder **28** is the same as the distance from center to center of lands **19** and **20**. The land **21** is preferably spaced from shoulder **28** a short distance to reduce the possibilities of sanding up about this land.

With the relationship described above, each of the swab rubbers **14** will have its intermediate section overlying a land when the several swabs are in the up position as shown in FIGURE 1. The extremities of the swab rubbers will overlie the grooves, and thus each swab rubber can rock about its associated land to misaligned position as illustrated in FIGURE 1. In locating land **21**, it is apparent that it could be positioned anywhere between the stop **28** and the lower end of the swab **14a** shown in dashed outline, as such location will permit the lower swab to misalign.

With the relationship of the several lands and grooves described above, it is apparent that when the swab rubbers, which are of equal length, move to their downward position as shown in FIGURE 2, each swab rubber overlies two lands to hold the swab rubbers in aligned position. It should be noted that the bore **14b** through the swab rubbers is slightly larger in diameter than the diameter of a circle in which the several lands extend. This permits the swab rubbers to slide longitudinally over the mandrel. The clearance, however, is such that with the swab rubbers in down position and engaged with two spaced lands, the swab rubbers are held in substantially aligned position.

It will be noted that as the swab rubbers move to down position in aligned condition, they engage each other and the lowermost swab rubber seats on shoulder **28** and seals therewith. This prevents flow through the several flutes **26**, and thus the swab rubbers function as check valves to control flow through the several flutes.

The operative position of the mandrel and swabs is shown in FIGURE 1 during running of the swab. The swab rubbers will drag against the wall of the tubing and will remain in their upper position during lowering of the mandrel. They thus will be able to misalign as shown in the drawings. As the swab falls through the liquid in the well, the liquid will pass up through flutes **26** and the swab may readily pass through such liquid. The swab rubbers may misalign relative to each other and to the mandrel so that they will readily pass through tight spots in the tubing.

After the swab is lowered to a desired level, it is raised and the several swab elements will move downwardly relative to the mandrel. The lowermost swab element will seat on shoulder **28** and the upper end of this swab element will terminate at a position overlying the land **20**. The next swab element will move down to position its lower extremity over the land **20** and abut against the lower swab element. This swab's upper extremity will overlie the land **19**. In like manner, if a third swab rubber is present it will straddle the groove **23** and be aligned by lands **18** and **19**. In this position, flow through the flutes is stopped and the several swab rubbers are held in aligned position with the mandrel and are in position to raise fluid in the well.

This invention is of particular value where swab elements of the type employing radial flanges are concerned, as these radial flanges may be relatively flexible and relatively incapable of centering themselves on the swab mandrel. It will be appreciated that as the swab mandrel is moved upwardly and a load of liquid is imposed on the swabs, that a substantial downward force is exerted on the swab rubbers. If they are not aligned with the mandrel at this time, they will probably be held in the position they assume at the time that a load is placed on the swab rubbers. If they were eccentric, excessive uneven wear would occur which would affect the life of the swab. It is, therefore, important that the swab rubbers be in aligned position so that they are automatically centered before a substantial load is imposed on the swab.

rubbers. Of course, there is no substantial problem in pulling the swab rubbers upwardly through eccentric or tight places as the swab rubbers may be readily pulled through any space through which they can be dropped. The several flanges may readily give to pass through bent, eccentric or tight places without affecting the operation of the swab.

It will be appreciated that by using the relatively small lands and the relatively long grooves, that substantial spaces are provided between the swab rubbers and the mandrel, and there is much less likelihood of sand lodging between the lands and the swab rubbers and preventing their proper operation.

In the explanation of the relative position of the lands and grooves, reference was made to the center of the lands. It will be appreciated that it is only necessary to have the several swabs engage lands, and adjacent extremities of the two swabs might engage any portion of a particular land and function properly, as the only purpose of the land is to align the swab rubbers.

While swab rubbers of the type having radial flanges are illustrated, it will be apparent that swab rubbers of any desired type may be utilized.

The foregoing disclosure and description of the invention are illustrative and explanatory thereof and various changes in the size, shape and materials, as well as in the details of the illustrated construction, may be made within the scope of the appended claims without departing from the spirit of the invention.

What is claimed is:

1. A swab assembly comprising,

a mandrel,
at least one swab rubber on said mandrel movable
between upper and lower positions on said mandrel,
cooperable means on said mandrel and each swab
rubber permitting misalignment of said mandrel and
each swab rubber when the swab rubbers are in their
upper position and aligning each swab rubber on said
mandrel when said swab rubbers are in their lower
position.

2. The swab assembly of claim 1 wherein said mandrel
is fluted to allow fluid flow therethrough when the swab
rubbers are in their upper positions, and wherein the
lower swab rubber sealingly engages a stop when the
swab rubbers are in their lower position to prevent flow
through said flutes.

3. The swab assembly of claim 1 wherein each swab
rubber comprises a plurality of generally radially ex-
tending resilient flexible flanges for engaging the wall of
a tubing.

4. A swab assembly comprising,
an elongate mandrel having a plurality of circumferen-
tially extending alternate lands and grooves on its
intermediate section,
enlarged upper and lower sections on said mandrel
above and below said intermediate section,
at least one swab rubber on the intermediate section,
each swab rubber having a bore therethrough loosely
and slidably receiving said lands,
said lower enlarged section providing a stop positioning
each swab rubber in engagement with two spaced
lands to center each swab rubber when in the down
position,
said upper enlarged section providing a stop positioning
each swab rubber with its intermediate section over
a land and its extremities over grooves to permit
misalignment of the mandrel and each swab rubber
with each swab rubber in its up position.

5. The swab assembly of claim 4 wherein the inter-
mediate section of the mandrel is fluted to provide for
flow of fluid with each swab rubber in its upper position
and wherein the lower mandrel section and a swab rub-
ber engage and close off the passageways provided by
said flutes when each swab rubber is in its lower position.

6. The swab assembly of claim 5 wherein each swab

rubber comprises a plurality of generally radially extending resilient flexible flanges for engaging the wall of the tubing.

7. A swab mandrel comprising,
an intermediate section and enlarged upper and lower
sections above and below said intermediate section,
said upper and lower sections providing stops to limit
travel of swabs on the intermediate section,
alternate lands and grooves on said intermediate section
with the distance between the upper section and
the center of the uppermost land being approximat-
ely one-half the distance between the center of the
uppermost land and the center of the uppermost
land and the center of the next uppermost land,
the distance between the lower section and the center
of the second lowermost land and the distance be-
10
15

tween any two intermediate lands being approxi-
mately equal.

8. The swab mandrel of claim 7 wherein the inter-
mediate section is fluted.
